IGNITION SYSTEM FOR MERCURY ARC
MUTATORS

Max Hürlimann, Wettingen, Switzerland, assignor to Aktiengesellschaft Brown, Boveri & Cie, Baden, Switzerland, a joint-stock company of Switzerland

Application September 29, 1948, Serial No. 51,823
In Switzerland October 28, 1947

9 Claims. (Cl. 315—263)

1

This invention relates to ignition systems for mercury arc mutators such as employed for the rectification of alternating current or the conversion of direct current to alternating current, and more particularly to ignition systems of the type which includes an exciter anode and a resistance igniter electrode.

Prior ignition systems of this type have usually included two sources of direct current; one being of low voltage to maintain an exciter space current between the mercury cathode and the exciter anode, and the other current source being of high voltage to furnish current impulses for re-igniting the starting device upon extinction of the cathode spot developed by the exciter current. Choke coils were included in the prior igniter circuits, and voltage variations across the choke coils were employed to actuate switches to deliver high voltage current impulses to the resistance igniter electrodes upon extinction of the cathode spot. Such ignition systems were open to the objections that a current source of high voltage was required to supply the ignition impulses and that current through the choke coil at the moment of ignition was practically zero and increased only gradually, these conditions being unfavorable for the initiation of ignition.

Objects of the present invention are to provide ignition systems which are not open to these objections. An object is to provide an ignition system for an ignition device of the exciter anode-resistance igniter electrode type, which system includes a choke coil in series with the ignition device and a low voltage source of direct current, and switch contacts in an auxiliary circuit bridged across the ignition device, the switch contacts being opened to deliver an igniting current impulse to the ignition device by the collapse of the magnetic field of the choke coil. More specifically, objects are to provide ignition systems of the character stated in which a relay winding is included in the series circuit of the choke coil for actuating the switch contacts or, alternatively, a synchronous motor is employed to actuate the switch contacts.

These and other objects and the advantages of the invention will be apparent from the following specification when taken with the accompanying drawings in which:

Fig. 1 is a schematic circuit diagram of an ignition system embodying the invention;

Fig. 2 is a fragmentary circuit diagram of a multiple break relay switch and arc-suppressing circuit which may be substituted for the single break relay switch of the Fig. 1 circuit; and

Fig. 3 is a schematic circuit diagram of a further embodiment of the invention.

2

In the drawing, the reference numeral 1 identifies the metal receptacle of a mercury arc mutator having a mercury cathode 2, an anode 3, and an ignition device comprising a resistance igniter electrode 4 combined with an exciter anode 5 as a single constructional unit, as described in United States Patent No. 2,435,357, Hans Keller and Charles Ehrensperger. The exciter anode 5 is electrically connected to the upper end of the ignition electrode, and is of disk shape with a depending rim spaced from the surface of the mercury cathode pool 2 to form therewith a small open-sided chamber within which the igniter electrode 4 is located.

15 A low voltage source of direct current for energizing the ignition system may be batteries but preferably, as illustrated, may take the form of a full-wave rectifier bridge 6 in the secondary circuit of a transformer 7, the primary circuit being connected through switch 8 to an alternating current source 9 which may be the network feeding the mercury arc rectifier or may be an auxiliary network. The igniter-exciter device 4, 5 is connected across the direct current source 6 by a circuit which includes, in series, a resistor 10, a choke or spark coil 11, the winding 12 of a relay having an armature 13, an adjustable resistor 14, the ignition device 4, 5, the mercury pool 2, and a lead 15. The relay armature 13 carries a contact *a* for bridging a pair of spaced back contacts *b*, *b* when the armature drops out upon a decrease in the relay current to a value somewhat less than the normal exciter or space current between the mercury cathode 2 and the exciter anode 5. The contacts *b*, *b* are connected by leads 16, 16' to the resistor 14 and to the return lead 15, respectively, whereby the closing of the relay or switch contacts completes an auxiliary circuit in shunt with the ignition device 4, 5 and resistor 14.

Upon closing the switch 8 to supply current to the rectifier bridge 6, the initial flow of direct current is through resistor 10, coil 11, relay winding 12, the auxiliary circuit through the switch 45 contacts and lead 15; and only a negligible current flows initially through resistor 14 and the resistance igniter electrode 4. The current increases rapidly to such value that relay armature 13 pulls in to open the auxiliary circuit at the relay contacts, thereby forcing the entire current through the choke coil 11 to flow through the resistor 14 and ignition electrode 4 since the electromotive force of the choke prevents a sudden change in the current value. The resulting current impulse through the igniter electrode vaporizes some of the mercury, thereby ionizing and reducing the resistance of the space path between

the mercury cathode pool 2 and the exciter anode 5 to substantially less than the resistance of the current path through the resistance igniter electrode 4. Arcing or space conduction is thus established between the exciter anode and the mercury cathode to maintain a cathode spot beneath or adjacent the exciter anode.

The values of resistors 13 and 14 are so adjusted that the exciter current through choke coil 11 after ignition is established is less than the ignition impulse current through the choke coil following the opening of the switch contacts in the auxiliary circuit. The exciter current through relay winding 12 is of sufficient magnitude to hold the relay armature 13 in attracted position to open the relay contacts. Upon interruption of the exciter current, the relay armature 13 drops out to close the auxiliary circuit momentarily, thereby increasing the current through choke coil 11 and relay winding 12 to pull relay armature 13 in again to open the auxiliary circuit. This develops a new current impulse through the igniter electrode 4 to initiate a new ignition operation. Ignition is quickly established with no delay since the choke coil 11 carries current prior to and at the moment of ignition.

A rapid and certain opening of the auxiliary circuit may be obtained by providing the relay with a plurality of sets of contacts $a, b, b'; a', b', b'$ and a'', b'', b'' arranged in series in the auxiliary circuit, Fig. 2. Arcing at the relay contacts may be suppressed by shunting one or more of the sets of relay contacts by a condenser 17 in series with a damping resistor 18.

The invention is not limited to ignition systems in which a cathode spot is maintained by a substantially continuous flow of exciter current but may be advantageously applied to igniter systems in which a cathode spot is cyclically established in synchronism with the alternating current input to or output from a mercury arc mutator. In such a system, as illustrated in Fig. 3, the series circuit which connects the igniter device 4, 5 across a direct current source 6 includes a resistor 13, choke coil 11 and resistor 14 similar to or identical with the corresponding elements of the Fig. 1 circuit but the starting relay 12, 13 is replaced by a synchronous motor 19 driving an arcuate contact 20 which is connected to choke coil 11 and which cyclically bridges a contact 21 connected to the return lead 15 and a contact 22 connected to the adjustable resistor 14. The engagement of moving contact 20 with contact 21 completes a charging circuit for establishing a current through the choke coil 11, and the separation of moving contact 20 from contact 21 opens this charging circuit to deliver a current impulse to the igniter-exciters 4, 5 over the contact 22 and the resistor 14, thereby to reignite the exciter anode 5 just prior to the instant when the voltage on the anode 3 becomes positive with respect to the mercury cathode 2. As compared with prior synchronous or cyclically energized ignition systems, this circuit has the advantage that a direct current source of relatively low voltage may be employed since the voltage pulse for firing the ignition electrode is produced at the choke coil 11.

It is to be understood that the invention is not limited to the particular ignition systems herein illustrated and described since various changes which may be made in the circuit elements and circuit arrangements fall within the spirit and scope of the invention as set forth in the following claims.

I claim:

1. An ignition system for mercury arc mutators having a mercury cathode and a resistance igniter electrode in contact with said cathode, said system comprising a source of direct current and a choke coil connected in series with said igniter electrode, an auxiliary circuit in shunt with said igniter electrode and including switch contacts, whereby said current source establishes a current through said choke coil and said auxiliary circuit when said switch contacts are closed, and means for opening said switch contacts, thereby to develop a current impulse through said igniter electrode.

2. An ignition system as recited in claim 1, in combination with an exciter anode electrically connected to said igniter electrode, and wherein said means for opening said switch contacts comprises a relay having a winding in series with said choke coil and said switch contacts; the pull-in current of the relay being of less magnitude than the exciter current established by said current source between the cathode and exciter anode upon ionization of the exciter anode-cathode space.

3. An ignition system as recited in claim 2, wherein said switch contacts comprise a series of sets of switch contacts connected in series.

4. An ignition system as recited in claim 1, in combination with an arc-suppressing circuit shunted across said switch contacts.

5. An ignition system as recited in claim 1, in combination with an exciter anode electrically connected to said resistance igniter electrode.

6. An ignition system as recited in claim 1, wherein said switch contacts comprise a pair of contacts electrically connected to opposite sides of said resistance igniter electrode, and a movable contact supported for rotation to bridge the contacts of said pair; and said means for opening said contacts comprises a synchronous motor for rotating said movable contact.

7. An ignition system as recited in claim 6, in combination with an exciter anode electrically connected to said starting electrode and having a rim flange spaced from the surface of the cathode and cooperating therewith to form an open-sided chamber within which said igniter electrode is located.

8. An ignition system for mercury arc mutators having a mercury cathode and a combined exciter anode-resistance igniter electrode, the igniter electrode being in contact with the mercury cathode; said igniter system comprising a source of direct current, a main circuit connecting said current source to said exciter anode-resistance igniter electrode, said circuit including in series a choke coil and resistance means, an auxiliary circuit including switch contacts and shunted across said exciter anode-resistance igniter electrode and a part of said resistance means, and relay means having a winding in series in said main circuit for opening said switch contacts of the auxiliary circuit.

9. An ignition system as recited in claim 8, wherein said resistance means includes resistors in said main circuit and at opposite sides of said auxiliary circuits to limit the current through said choke coil after opening of said switch contacts to a lesser value than the current through the choke coil when said switch contacts are closed.

MAX HÜRLIMANN.
